UNITED STATES PATENT OFFICE.

JESSE ALEXANDER, OF BROOKLYN, NEW YORK, ASSIGNOR, BY MESNE ASSIGNMENTS, TO LEE ALEXANDER, KITTIE ALEXANDER, JR., JESSE ALEXANDER, JR., AND TYVE ALEXANDER.

TYPE-WRITER-CARRIAGE STOP

No. 833,286.

Specification of Letters Patent.

Patented Oct. 16, 1906.

Original application filed June 2, 1902, Serial No. 109,925. Divided and this application filed March 9, 1903. Serial No. 146,902.

To all whom it may concern:

Be it known that I, JESSE ALEXANDER, a citizen of the United States, residing at Brooklyn, in the county of Kings, State of New York, have invented certain new and useful Improvements in Type-Writer-Carriage Stops, of which the following is a full, clear, and exact description.

My invention relates to improvements in type-writers, and particularly to the carriage-stop construction of a machine of that type as more particularly and fully shown, described, and claimed in my application, Serial No. 109,925, filed June 2, 1902, from which this is a divisional application.

The object of this invention is to provide simple, efficient, and durable means which may be easily adjusted for effecting the automatic stopping of the carriage at definite points in its travel either to the right or to the left, both for the ordinary operation of the machine and for its operation in tabulating or the like.

The invention consists in providing longitudinally-adjustable stops which coact with stationary members for the purpose of providing definite stopping-points for the carriage in its ordinary travel from right to left and from left to right and also in providing an independent set of stops which are adjustable longitudinally of the carriage for coöperation with a jump or tabulating mechanism, by means of which the carriage may be moved through the desired number of spaces by the simple depression of a key. The first class—namely, the marginal stops—are provided at the left and right hand end of the machine. The second set—namely, the jump-stops—are provided, as desired, either singly or in plurality and may be adjusted or varied in position as desired.

In the drawings, Figure 1 is a plan view of those parts of the type-writer which embody the improvements of this invention, part being broken away and part in section. Fig. 2 is a side elevation of parts of the automatic jumping mechanism. Fig. 3 is a cross-section and side elevation of the carriage construction, together with the marginal and "jump" stops. Fig. 4 is a front elevation of part of the jumping mechanism. Fig. 5 is a

rear view of one end of the construction. Fig. 6 is a view of the carriage and platen side plates or frames.

The reference-numerals which are shown in the drawings are substantially the same as those appended to the drawings in the original application, from which this is a division.

2 is a platen rotatably supported in the side plates 7 and having a shaft 8 and handles or operating-knobs 9 at the ends. The side plates 7 are connected to the side frames 22 by means of the intermediate members 72 and have a pivotal mounting with respect thereto for the purpose of permitting the platen to be shifted from the lower to upper case position.

221 is a bar which connects the carriage side plates 22 and indirectly the platen side frames 7 and which itself is removably secured to a guide-sleeve 23 by a thumb-screw 232. This sleeve is mounted to slide longitudinally of the rear track-bar 24. The bar 222 connects the carriage side plates at the front and is suitably guided—for instance, as shown in my application, Serial No. 146,901, filed herewith. The pin 722, projecting from the platen side plate, has a limited vertical movement in the notch 225 to permit the shifting of the platen.

131 is an auxiliary guide-rail which acts in coöperation with the roller 91 when the platen is shifted.

The carriage may be guided and given a normal impulse by any suitable means or as shown in my application filed herewith.

26 is a rack carried by the pivoted rod 260. 261 is a handle attached to the rod 260, by means of which it may be tilted about its pivotal supports in the side frames 22.

264 is a spring giving the rack a normal engagement with the gear 27. 28 is a shaft which carries this gear 27 at the upper end and at the lower end carries a ratchet 29, constituting part of the escapement mechanism, by means of which the step-by-step movement of the carriage is limited.

The release of the carriage or movement from right to left may be effected by a jump or tabulating device, as shown particularly in Fig. 2. 37 is a key-bar pivoted suitably in the machine for operating the jumping mech-

anism. 370 is a rod connected, by means of the post 371, to the lever 372. This lever 372 is pivoted to the frame of the machine and has a rocking movement in a vertical plane. Beyond the pivotal point this lever 372 carries a projection or pin 373, which stands underneath the edge of the rack 26 of the escapement mechanism. The end of this pin 373 is preferably beveled, as shown in Fig. 2, in order to effect a more perfect cooperation with the rack 26. When the key-bar 37 is depressed, the lever 372 is tilted, and the pin 373 lifts the rack 26 or rotates it about its axis on the shaft 260 to a sufficient degree to release the teeth of the rack from the teeth of the gear 27. The carriage is then free to move under its normal impulse from right to left without the interference of the ordinary escapement mechanism. By retaining the key 37 in a depressed position with some pressure applied the pin 373 acts as a brake upon the movement of the carriage, there being a frictional engagement with the under side of the rack 26. By this means and by varying the pressure the speed of travel of the carriage and its distance may be controlled. It is desirable, however, that adjustable stops be provided to coöperate with the carriage, so that it may stop at definite points as desired.

76 is a shaft which has bearings in the side frames 22 22.

77 is a jump-stop which is mounted so as to longitudinally slide upon the shaft 76, but to rotate therewith, the shaft being preferably flattened on one side to effect this coöperation.

761 is a spring on shaft 76, which normally tends to hold the lower part of the stop 77 to the rear and in engagement with the teeth of a notched plate 78, which is carried by the carriage-bar 221.

79 is a scale mounted so as to enable the operator to adjust the stop 77 in a position as desired.

The heel 771 of the stop 77 is adapted to engage with the teeth of the plate 78. The spring 761 will hold the stop in engagement with this plate, and it will be obvious that the stop may be adjusted longitudinally on the shaft 76 to any position as desired. Any number of these stops 77 may be provided and adjusted at the desired points along the rod or shaft 76.

55 The toe 772 of the stop 77 when in its normal position stands in such a position that if the carriage is moved longitudinally when the stop key-bar is depressed the shoulder 374 of the lever 372 will intercept the stop, and thus arrest the movement of the carriage from right to left. When the key-bar 37 is released, the shoulder 374 of course moves downward and free from the toe of the stop. At the same time the pin 373 releases

the rack 26 and allows it to come into its normal engagement with the gear 27. The mechanism is then in position to be operated, as usual. The carriage may therefore be moved longitudinally by manually disengaging the rack 26 from the gear 27 or automatically by depressing the key 37. When it is thus automatically released, the movement will continue until the toe of the stop contacts with the shoulder 374. The position of the stop on the shaft 76 determines obviously the distance through which the carriage may be thus automatically moved.

38 is a marginal stop which is mounted on the guide-rod 24 at the rear and adapted to be adjusted longitudinally thereon

381 is a beveled point or projection from the lower front edge of the stop 38, which is adapted to engage with the teeth of a notched plate 382, carried by the frame of the machine. This plate is provided with a scale in order to guide the operator in adjusting the stop to its proper position.

383 is a spring which is situated in a recess in the stop 38 and the tension of which against the rod 24 may be adjusted by the screw 384. The tension of this spring 383 tends to hold the stop 38, with its projection 381, in engagement with the rack or toothed plate 382. The stop may, however, be rotated about the rod 24 until the end of the spring 383 slips about the corner of the rod, and at this time the stop will be held out of engagement with the teeth of the plate 382. In this way the operator may, if it is desired, disengage the stop 38, and it will remain in its disengaged position at an angle corresponding to the angle between the faces of the rod 24—in this instance ninety degrees, since the rod is squared. The horizontal rearwardly-extending handle of the stop 38 acts as a weight to assist the spring 383 in holding the stop in its engagement with the teeth of the shaft 382.

39 is a similar stop or dog mounted to be adjusted on the rod 24, but with its projection 391 oppositely positioned from the tooth of the stop 38. Similarly, the toothed plate 392 has its teeth oppositely positioned from the teeth of the plate 382. The carriage, which is mounted on the guide-sleeve 23, will therefore be limited in its longitudinal movement either to the left or to the right by the positions of the stops or dogs 38 39, against either one of which the corresponding end of the sleeve 23 will abut.

These stops may be very readily adjusted in longitudinal positions and disengaged, if desired. The construction is simple and reliable. The stops 38 may be readily attached to in any number or removed from the rod 24 at any time. The operation of the platen-shifting mechanism and the operation of the stop mechanism do not interfere with one another under any conditions, and the parts are

so constructed that the severe shock to which they are subjected when the stop is operated carelessly does not injure the parts, the carriage-frames and platen side plates being especially designed for this purpose.

What I claim is—

1. In a type-writer construction, the combination of a carriage including side plates, a bar connecting them, a guide-sleeve removably connected to said bar and a guide-rod on the machine-frame, and a spring-pressed marginal stop adjustable on said rod and adapted to coact with said guide-sleeve.

2. In a type-writer construction, the combination of a carriage including side plates, a bar connecting them, a guide-sleeve removably connected to said bar, a guide-rod on the machine-frame, and a marginal stop adjustable on said rod and adapted to coact with said guide-sleeve, a rack and a spring for pressing against the flat face of said rod and holding said stop against said rack.

3. A type-writer construction including a pair of carriage side frames, platen side plates pivotally connected to said frames, a bar connecting said frames and plates, a shaft pivoted in said frames, a rack carried by said shaft, escapement mechanism coacting with said rack and a key-controlled means for disengaging the rack from said escapement mechanism.

4. A type-writer construction including a pair of carriage side frames, platen side plates pivotally connected to said frames, a bar connecting said frames and plates, a shaft pivoted in said frames, a rack carried by said shaft, escapement mechanism coacting with said rack and a key-controlled means for disengaging the rack from said escapement mechanism including a key-bar, a pivoted lever and a rod connecting said key-bar and said lever.

5. A type-writer construction including a pair of carriage side frames, platen side plates pivotally connected to said frames, a bar connecting said frames and plates, a shaft pivoted in said frames, a rack carried by said shaft, escapement mechanism coacting with said rack and a key-controlled means for disengaging the rack from said escapement mechanism, a shaft or rod and an adjustable stop carried thereby and adapted to be engaged by the mechanism which also operates to disengage the rack from the feed mechanism.

6. A type-writer construction including a longitudinally-movable carriage having side frames, a pivotally-mounted rack carried thereby and forming one element of an escapement mechanism, a key-bar, a pivoted lever and a connecting-rod between said key-bar and one end of said lever whereby by the depression of said key-bar said rack may be moved about its pivot, a shaft or rod forming

a rear guide-track and an adjustable stop carried thereby and adapted to be engaged by the mechanism which also operates to disengage the rack from the feed mechanism.

7. A type-writer construction including a longitudinally-movable carriage, a pivotally-mounted rack carried thereby and forming one element of an escapement mechanism, a key-bar, a pivoted lever and connecting-rod, between said key-bar and one end of said lever whereby by the depression of said key-bar said rack may be moved about its pivot, and the carriage moved longitudinally but frictionally controlled, a shaft or rod forming a rear guide-track, and an adjustable stop carried thereby and adapted to be engaged by the mechanism which also operates to disengage the rack from the feed mechanism.

8. A type-writer construction including a carriage, an angular guide-rod, a longitudinally-movable sleeve mounted thereon, a stop mounted on said guide-rod, a spring acting in a recess in said stop and coöperating with a face of said rod for yieldingly holding the said stop in its operative position.

9. A type-writer construction including a carriage, an angular guide-rod, a longitudinally-movable sleeve mounted thereon, a stop mounted on said guide-rod, a spring acting in a recess in said stop and coöperating with a face of said rod for yieldingly holding the said stop in its operative position, and a screw coöperating with said spring.

10. A type-writer construction including a carriage, a guide-rod, a longitudinally-movable sleeve mounted thereon, a weighted stop mounted on said guide-rod, a spring acting in a recess in said stop and coöperating with said rod for holding the said stop in its operative position and a stationary plate with its teeth to the rear and engaged by said stop.

11. A type-writer construction including a stationary guide-rod, a sleeve mounted to slide thereon, adjustable stops mounted on said guide-rod at either end to act in conjunction with said sleeve as it moves longitudinally on said rod and handles projecting to the rear for adjusting said stops and weighting them, and a carriage construction connected to said sleeve.

12. A type-writer construction including a guide-rod, a sleeve adapted to slide thereon, a carriage construction carried by said sleeve and comprising side frames, a bar connecting the same, a notched plate carried by said bar, a shaft or rod, a longitudinally-adjustable stop carried by said rod and normally in engagement with the teeth of said plate and key-controlled means for interposition in front of said stop.

13. A type-writer construction including a guide-rod, a sleeve adapted to slide thereon,

a carriage construction carried by said sleeve and comprising side frames, a bar connecting the same, a notched plate carried by said bar, a shaft or rod, a longitudinally-adjustable stop carried by said rod and a spring for normally holding said stop in engagement with the teeth of said plate and key-controlled means for engaging said stop.

14. A type-writer construction including a guide-rod, a sleeve adapted to slide thereon, a carriage construction carried by said sleeve and comprising side frames, a bar connecting the same, a notched plate carried by said bar, a shaft or rod, a longitudinally-adjustable stop carried by said rod and normally in engagement with the teeth of said plate, and a key-controlled stop-lever adapted to be moved so as to intercept the longitudinal movement of the carriage by means of said latter stops.

movement of the carriage by means of said stop. 20

15. A type-writer construction including a stationary guide-rod, a sleeve mounted to slide thereon, adjustable stops mounted on said guide-rod at either end to act in conjunction with said sleeve as it moves longitudinally on said rod, and a carriage construction connected to said sleeve, a rod, adjustable stops mounted thereon and a key-controlled stop-lever adapted to be moved so as to intercept the longitudinal movement of the carriage by means of said latter stops. 25 30
